Application filed June 21, 1901. Serial No. 65,512. Term of patent 3½ years.

To all whom it may concern:

Be it known that we, THEODORE L. POPP and CARL F. GEYER, citizens of the United States, residing at Buffalo, in the county of Erie and State of New York, have invented and produced a new and original Design for the Case of a Jack-in-a-Box or Similar Article, of which the following is a specification, reference being had to the accompanying drawings, forming a part thereof.

This design relates to the configuration and ornamentation of the case of a "jack-in-a-box" or similar article.

In the accompanying drawings, Figure 1 is a perspective view of a jack-in-a-box case embodying our design. Fig. 2 is a cross-section thereof.

Like letters of reference refer to like parts in both figures.

As shown in the drawings, the leading or material feature of our design consists of a circular case A, a radial arm or extension B, projecting from one side of the case, the figure C of an incandescent electric lamp arranged upon the front side of the case, and the representation of an Indian head D, surmounting the lamp and merging into the contracted neck e thereof.

What we claim is—

The design for the case of a jack-in-a-box or similar article, substantially as herein shown and described.
